UNITED STATES PATENT OFFICE.

JOHN A. PILCHER, OF ROANOKE, VIRGINIA.

SIX-WHEEL TRUCK FOR RAILWAY-CARS.

1,165,206.

Specification of Letters Patent. Patented Dec. 21, 1915.

Application filed August 16, 1913. Serial No. 785,143

To all whom it may concern:

Be it known that I, JOHN A. PILCHER, a citizen of the United States, residing at Roanoke, in the county of Roanoke and State of Virginia, have invented certain new and useful Improvements in Six-Wheel Trucks for Railway-Cars, of which the following is a specification.

This invention relates to six-wheel trucks for railway cars and has for its object to provide means for varying the locations of the springs in trucks of the type having articulated side frames, such as shown and described in Patent #1,054,697, Lewis-Pilcher, March 4th, 1913. In this and similar trucks it is necessary that the springs be located so that the centers of the groups come at a point approximately two-thirds of the distance between the middle axle and the outer ones. This entails limitations on the construction of the various parts that are sometimes undesirable. In this invention I am enabled to overcome this difficulty, at the same time maintaining the equal distribution of the weight among the three axles.

In the drawings, Figure 1 represents a side elevation of the truck of my invention, Fig. 2 a partial plan view of the same and Fig. 3 a sectional elevation taken on the line A B, Fig. 2. Figs. 4 and 5 represent in side and end elevations respectively the equalizing bar as used in the construction shown in Figs. 1, 2 and 3. Fig. 6 is a transverse section of the truck taken on the line C D, Fig. 2. Fig. 7 is a side elevation of a truck having a modified form of equalizing bar and Fig. 8 shows, in side elevation, a detail of this modified form of equalizing bar. Figs. 9 and 10 are side and end elevations respectively of the hanger used with either form of equalizing bar. Fig. 11 shows a side elevation of the side frame to which is secured the middle journal box and one of the outer journal boxes and Fig. 12 shows a side elevation of the side frame to which is secured the other of the outer journal boxes.

Referring now to the drawings in which like parts are given the same reference numbers wherever they occur, 1 represents an outer truck wheel, 2 a middle wheel and 3 one of the other outer wheels. These wheels 1, 2 and 3 as well as those on the opposite side of the truck are secured to the axles, 4,

5 and 6 in the customary manner and the axles are journaled in the customary journal boxes 7, 8 and 9. The side frames 10 and 11 are connected at their inner ends at 12 by any suitable form of knuckle joint so arranged that one side frame may have movement relative to the other by pivoting about 12, and by this articulation the various parts of the truck may readily respond to variations and irregularities in the condition of the track. To the side frame 10 is secured at its outer end by means of the bolts 13 and 14 the tie bar 14 the journal box 7, while at its inner end the box 8 is secured to the said side frame 10 by means of the bolts 15 and tie bar 16. To the outer end of the side frame 11 is secured by means of the bolts 17 and tie bar 18 the journal box 9.

The weight of the car is carried on the truck center plate 19 which is integral with or secured to the truck bolster 20. At 21 are side bearings disposed to agree with the side 75 bearings on the car body. The truck bolster is provided with arms 22 and 23 which extend outwardly through suitable windows 24 and 25 in the side frames 10 and 11. These outwardly extending arms are provided with 80 vertically disposed guides 26 and 27 which co-operate with similarly disposed guides 28 and 29 on the side frames 10 and 11. In order that the bolster arms 22 and 23 may be entered through the windows 24 and 25 of 85 the side frames the outer guides 27 are made detachable from the bolster.

While the bolster shown is in the shape of a platform casting yet it might be as readily made from structural or pressed steel and 90 also I wish it to be understood that while the previously described method of entering and guiding the bolster arms in the side frames is a perfectly satisfactory one yet other means might be employed without de- 95 parting from the essential features of my invention.

For supporting the bolster, springs 30 are placed under the arms 22 and 23. In the customary truck of this type these springs 100 30 rest on the bottom portion 31 of the side frames immediately under the window openings 24 and 25. When this is done it is necessary, as previously stated, that the centers of the groups of springs come at points longitudinally of the frames approximately one-

third of the distance from an outer axle to the middle axle, thus equalizing the loads on the three axles. In the truck of my invention, however, I rest the springs 30 on a 5 spring seat 32 which in turn is supported by equalizing bars 33 which extend from the side frame 10 to the side frame 11 and are hung from these side frames by links 34. The connection of the links 34 to the side 10 frames is pivotal as shown at 35 as is also the connection of these links to the equalizing bars at 36.

The spring seats 32 are so disposed through the window openings 24 and 25 15 that the bottom of the spring seats will not ride on the top of the members 31 of the side frames. This allows the necessary movement of the links 34 and equalizing bars 33 and insures the bolster load coming 20 on the equalizing bars 33 and not directly on the frames 10 and 11. It is now evident that if the points of connection 35 of the links 34 to the side frames be made at points 25 longitudinally of the frames approximately one-third of the distance between an outer axle and the middle axle, the load of the bolster will equalize among the three axles, no matter at what position along the equalizing bars the spring loads are applied to 30 them, provided of course that the loads on the equalizing bars are symmetrically disposed.

While in the drawings I have shown two 35 equalizing bars at each side of a truck, one disposed along either side of the two side frames, yet in some instances it might be desirable to alter the form of the equalizing 40 bar to suit special conditions of design. Such an alternate arrangement is shown in Figs. 7 and 8 when the clearance under the middle journal box is not sufficient to admit of the construction shown in Figs. 1 to 6 inclusive. To meet such a condition I would 45 make the equalizing bar in the form of two bell crank levers 37 and 38 with a tie bar 39 joining them at the bottom. The connection of the two bell crank levers at 40 50 may be pivotal or rigid as may also the connections 41 and 42 of the tie bar 39. But the connections 41 and 42 should preferably be such that the tie bar may be readily removed for dropping the middle axle which will 55 necessarily extend out through the triangularly shaped opening formed by the two inclined arms of the bell crank levers and the tie bar 39. In some cases, also, the equalizing 60 bars will be placed above the side frames 65 with the ends of the equalizing bars resting on the side frames or on rollers, in which cases the links 34 would not be required. In this construction the spring loads would be transferred to the equalizing bars preferably by hangers or stirrups. Also, the ar-

ticulated side frames might be made as simple beams extending either over or under the bolster and having the axle boxes secured to them. The bolster might either rest on the springs or be hung from them. 70

From this it is seen that those skilled in the art might make various changes in the construction from that shown without departing from the spirit of my invention.

Having thus described my invention what 75 I claim as new and desire to secure by Letters Patent is,

1. In a six-wheel truck for railway cars, the combination with a bolster of springs 80 for supporting the same, a plurality of axles and oil boxes, side frames extending between adjacent oil boxes and having openings therein adapted to guide the said bolster, and equalizers adapted to form seats for the said springs, the said equalizers being supported by the said side frames. 85

2. In a six wheel truck for railway cars the combination of a bolster, springs for supporting the same, articulated side frames 90 having openings to receive the said bolster and springs, and an equalizing bar adapted to transfer the load from the springs to the said side frames.

3. In a six wheel truck for railway cars 95 the combination of a bolster, springs for supporting the same, articulated side frames having openings to receive the said bolster and springs and being further adapted to receive and support the axle boxes, and an equalizing bar adapted to transfer the load 100 from the springs to the said side frames.

4. In a six wheel truck for railway cars the combination of a bolster, springs for supporting the same, articulated side frames 105 having openings to receive the said bolster and springs, one of said articulated side frames being provided with means for securing thereto the axle boxes for the middle and one of the outer axles and the other of said articulated side frames being provided with means for securing thereto the axle box 110 for the other of the outer axles, and an equalizing bar adapted to transfer the load from the springs to the said side frames. 115

5. In a six wheel truck for railway cars the combination of a bolster, springs for supporting the same, articulated side frames having openings to receive the said bolster and springs, equalizing bars adapted to support the said springs and links adapted to 120 transfer the load from the equalizing bars to the said side frames.

6. In a six-wheel truck for railway cars, a plurality of axles and oil boxes in combination with a bolster, yielding supporting means for said bolster comprising side frames, equalizers and springs, the said side frames being supported by the said oil boxes, the equalizers by the side frames and the bolster by the said equalizers, and the 125 130

said springs being interposed between the said equalizers and the said bolster, the said side frames forming vertical slide ways for the movement of the said bolster on the said springs, the said equalizers being disposed along the sides of the said side frames and having swinging connection therewith.

In testimony whereof I affix my signature in presence of two witnesses.

JOHN A. PILCHER.
